LAMP

John B. Dickson, Huntington Woods, Mich., assignor to Chrysler Corporation, Highland Park, Mich., a corporation of Delaware

Application February 8, 1937, Serial No. 124,576

1 Claim. (Cl. 240—41.5)

This invention relates to improvements in lamps.

More particularly, the invention pertains to improved adjustable light beam projecting lamps for vehicles.

One of the main objects of the invention is to provide means for adjustably removably mounting in a lamp structure, an electric bulb unit of the type which includes a permanently, hermetically sealed assembly comprising integrally associated unitary lens and reflector portions having a filament enveloped therebetween.

Further objects of the invention are to provide an improved casing for a lamp unit of the foregoing character which is adjustable from the exterior of the lamp structure in which it is mounted in order to facilitate convenient focusing of the light beam; to provide improved means for securely releasably holding a casing of this character and the lamp unit mounted therein, in a selected position of adjustment; and to provide releasable securing means of this kind which are accessible from the exterior of the lamp structure to accommodate focusing of the lamp without requiring disassembly thereof.

Still further objects of the invention are to provide a casing for the lamp unit assembly from which the lamp unit is conveniently removable; to provide an assembly of this character in which the lamp unit is yieldably held in its normal position without endangering the glass portions thereof to chipping or fracture by glass engaging clamping or similar means; to provide an interfitting lamp casing and bulb unit of the foregoing kind which, when in one relative angular position, are normally inseparable and which, when in another relative angular position, accommodates removal of the bulb unit from the casing; and to provide means for supporting a lamp bulb unit of this character independently of its terminal.

Illustrative embodiments of the invention are shown in the accompanying drawings, in which:

Fig. 1 is a fragmentary vertical sectional view of a vehicle head lamp embodying the invention.

Fig. 2 is a fragmentary front elevational view of the lamp shown in Fig. 1.

Fig. 3 is a horizontal sectional view taken on the line 3—3 of Fig. 1.

Fig. 4 is a fragmentary front elevational view, partly in section, showing a further development of the invention.

In the form of the invention illustrated in Figs. 1 to 3, inclusive, the lamp comprises a housing structure 10, preferably comprising a die cast-

ing which is securable to a portion of an automobile, generally designated by the numeral 11 in Fig. 1. The housing 10 has a generally circular opening 12 in its front side which is surrounded by a restricting lip 13. Mounted in the opening 12 is a dome shaped casing 14, preferably formed of sheet metal. The front end portion of the casing 14 protrudes externally of the housing 10 and is provided with an opening 15 which is also of generally circular shape. A rounded flange 16, formed integrally on the casing 14, surrounds and constricts the opening 15 therein. The flange is preferably somewhat resiliently yieldable and deformable. Diametrically opposite portions of the flange 16 are cut away, as illustrated at 17 in Fig. 2, in order to increase the diameter of the opening throughout a limited extent thereof.

An electric light bulb, generally designated by the numeral 18, is removably mounted in the opening 15 of the casing 14. This light bulb comprises hermetically, permanently sealed together glass lens and reflector portions 19 and 20, respectively, which envelopes a filament 21. The reflector portion 20 has a reflecting finish 20' on its internal surface. Formed at the region of the junction of the lens and reflector portions 19 and 20, which comprises the part of bulb 18 of maximum diameter, is a rim 22 having a forward portion which conforms in curvature to the rounded flange 16 of the casing 14. The enlarged diameter provided by the cut-away portions of the flange 16 accommodate edgewise insertion of the bulb 18 into the interior of the casing 14, wherein it may be turned to bring it to the position illustrated in Fig. 1 in order to bring the rim 22 into engagement with the flange 16.

The electric light bulb 18 is yieldably held against inward movement relative to the casing 14 by resilient sheet metal strips 23 which are secured to the casing 14 and which yieldably bear against the external side of the reflector portion 20 of the bulb 18. Two or more of these resilient strips 23 are preferably provided and so located as not to interfere with the removal and replacement of the lamp 18. The lamp 18 may be removed from the casing by urging it inwardly thereof until the rim 22 is separated from the flange 16 sufficiently to enable turning of the lamp bulb so that it may be moved outwardly of the casing in an edge-wise direction.

The casing is releasably held in a selected position of adjustment by a plate 24 which is swingably mounted on the housing 10 by one or more screws 25, as illustrated in Fig. 1. The screw 25

has a shank portion 26 which passes through an aperture 27 in the plate 24 and which abuts a shoulder of the housing 10 in order to prevent clamping of the plate 24 and to accommodate 5 slight swinging movement thereof with respect to the housing. Formed in the intermediate portion of the plate 24 is a circular opening 28 in which the inner extremity of the casing 14 is received. The plate 24 may be urged against the inner extremity of the casing 14 by a screw 29 threaded in an opening 30 in the plate 24 and having an external head portion 31 located externally of the housing 10 and accessible from the exterior thereof. When the plate 24 is released the casing 14 10 and light bulb 18 carried thereby may be adjustably varied in position to direct the light beam emitted from the bulb in any desired course, the movement of the casing 14 relative to the housing 10 being of a universal nature and capable of 15 being produced merely by pressing upon the external portion of the casing 14 which is exposed at the front of the lamp.

The lamp 18 is provided with a pair of terminal posts 32 which are receivable in terminal clips 33 25 and 34, as illustrated in Fig. 3. The terminal clip 33 is preferably connected by a wire 35 with the positive terminal of the battery of the vehicle and the terminal clip 34 is grounded on the casing 14 by a wire 36. The wires 35 and 36 are of sufficient length to accommodate removal of the bulb 18 from the casing 14 without disconnecting the terminal clips from the posts and in order to accommodate connection of the wires with the terminal posts of the bulb while the latter is held 30 externally of the casing 14.

In a lamp of this character the lens and reflector portions of the bulb are held in fixed relationship with respect to each other and with respect to the filament 21 under all conditions and 40 the bulb may be properly positioned and securely held in selected positions of adjustment, in order to suitably direct a beam of light from the lamp, by the casing 14 which has a flange surface of substantial extent in contact with the bulb.

45 In the form of the invention illustrated in Fig. 4, all parts of the lamp structure with the exception of the flange 16' and bead 22' of the bulb are substantially identical to those described in connection with Figs. 1 to 3. The flange 16' of the lamp illustrated in Fig. 4 is of uniform width throughout its entire circumferential extent, but the bead of the light bulb 18 has a reduced diameter by reason of its being cut away at diametrically spaced locations designated by the numeral 50 55 37. The reduced diameter of the bulb facilitates

edge-wise insertion of the latter into the interior of the casing, after which it may be rotated to its normal position.

Neither the flange of the casing 14 nor the rim 22 of the light bulb 18 necessarily has to be cut away if the casing and its flange are made of suitable resiliency yieldable and deformable sheet metal. If the casing and flange comprises yieldable and deformable sheet metal, then the flange 16 thereof may be deformed by squeezing the open side of the casing into generally elliptical shape to accommodate insertion of the bulb thereinto.

In a motor vehicle it is sometimes desirable to employ a pair of headlights of different sizes, one for high beam operation and the other for low beam operation. When this is desired, a smaller light bulb 38 of substantially identical construction may be mounted in the same manner as the bulb 18.

Although but several specific embodiments of the invention are herein shown and described, it will be understood that various changes in the size, shape and arrangement of parts may be made without departing from the spirit of my invention.

What I claim is:

A lamp including an outer housing having a light outlet opening and an adjacent aperture in its front face portion, a casing adjustably mounted in said opening comprising a dome-shaped structure universally movable with respect to said housing, said casing having an open external end, an electric light bulb mounted in the open end of said casing comprising permanently hermetically sealed lens and reflector portions having a filament enveloped by the latter, a securing plate within said housing having an opening therein for receiving an inner end of said casing of smaller cross section than the maximum cross section of said casing, a support for swingably mounting said plate on an internal portion of said housing comprising an anchoring member extending through an oversized opening in said plate and an abutment surface for holding said anchoring member against clamping said plate to said housing, and releasable means for urging said plate against said casing to releasably hold said casing in an adjusted position, said releasable means comprising a screw extending through said aperture of said front portion of said housing having a head located externally of the latter and a shank portion threaded in an aperture of said plate located opposite from said plate support.

JOHN B. DICKSON.
